UNITED STATES PATENT OFFICE.

ALBERT P. KOMOW, OF BROOKLYN, NEW YORK, ASSIGNOR TO UNITED STATES CLOTH CUTTING MACHINE CO., INC., OF NEW YORK, N. Y., A CORPORATION OF NEW YORK.

ELECTRIC CLOTH-CUTTING MACHINE.

1,244,055.

Specification of Letters Patent. Patented Oct. 23, 1917.

Application filed March 25, 1916. Serial No. 86,533.

To all whom it may concern:

Be it known that I, ALBERT P. KOMOW, a citizen of the United States, and a resident of the borough of Brooklyn, in the county of Kings and State of New York, have invented certain new and useful Improvements in Electric Cloth-Cutting Machines, of which the following is a specification.

10 One of the objects of the invention is to increase the ease and accuracy with which electric cloth-cutting machines may be operated, by affording the operator a clear view of the region where the cutting is taking place. In the earlier forms of electric cloth-cutting machines, the motor for driving the knife was bulky in its arrangement and seriously obstructed the view. Subsequently there was an endeavor to reduce 20 the transverse width of the motor. In the present invention I make no attempt to minimize the total width of the motor cross-wise of the machine, recognizing that a clear line of sight is required only at the side of the machine where the knife is located, and that it is immaterial if the motor projects to a substantial distance at the opposite side. I accordingly utilize a motor having a single horse-shoe field magnet with its field 30 windings disposed in projecting relation at the side of the machine remote from the knife, the overhang of the motor at the knife side being comparatively slight. By this same means the rearward overhang of 35 the motor is also reduced, which enables the hand grip to be moved closer to the standard, thereby increasing the ease and certainty with which the operator may move the machine.

40 Another object of the invention is to provide a simple and superior unitary device for operating the guard and grinder. This means comprises an operating member movable longitudinally of the machine and carrying inclines serving, respectively, to depress the grinder and to swing the guard outward away from the knife edge. The grinder, instead of being mounted to swing through a wide arc as is customary, is constructed and supported to slide vertically, whereby the grinder disks may be disposed in non-projecting relation beneath the overhang of the motor and may be brought into and out of action by a movement of small 55 extent. The guard, as herein constructed,

is mounted to swing about a vertical axis at its rear portion, and is normally locked in guarding relation to the knife by means of a hook carried by the longitudinally movable operating member.

60 The invention also comprises a novel and advantageous mounting for the individual grinder disks, supporting the same firmly against displacement and permitting quick adjustment.

65 Still another object is to provide a cloth raiser, which carries the goods toward the knife rather than away from it when brought into action. This is accomplished by so constructing and mounting the cloth raiser that it has a simultaneous longitudinal and tilting movement, being fulcrumed slidably upon the base and actuated by suitable linkage adapted to exert rearward draft upon a portion of the raiser projecting downward 75 through a slot or slots in the base.

70 Another object is to provide an improved construction and arrangement of the knife and its large gear and the ball bearing whereby these are journaled in the standard, 80 the advantages being ready removability of the knife and gear, leaving the ball bearing in the standard, and the exclusion of dust from the ball bearings without the necessity of special provisions to that end, because of 85 the tortuous path which particles must traverse before reaching the bearing.

These and other features and advantages 90 of the invention will become apparent as the specification proceeds and the novel parts and combinations will be more particularly 95 pointed out in the appended claims.

In the drawings:

Figure 1 is a side elevation of a machine looking at the knife side, with half of the 95 superstructure in vertical section, the guard and grinder being shown in normal position;

Fig. 2 is a plan view of the machine with the superstructure half in horizontal section;

Fig. 3 is a front elevation with the lower parts broken away and in section and the guard and grinder brought into the positions which they occupy when the knife is 105 sharpened;

Fig. 4 is a disassembled plan view of the field frame, the arrangement of this view being selected to correspond with that of Fig. 3;

Fig. 5 is an enlarged view, partly in horizontal section and partly in plan, illustrating the knife guard and operating means, and employing broken lines to illustrate the 5 actuated positions of these parts;

Fig. 6 is a side elevation of one of the grinder disks, showing its mounting in the bracket arm;

Fig. 7 is a vertical section through Fig. 10, taken in the plane of the axis;

Fig. 8 is a fragmentary side sectional elevation of parts at the lower portion of the machine, showing the cloth raiser and its operating mechanism in actuated condition;

Fig. 9 is a similar view with the parts in normal position;

Fig. 10 is a view of these parts in bottom plan; and

Fig. 11 is a vertical transverse section 20 through the standard and adjacent parts, showing more particularly the mounting and relation of the knife, gear and the ball bearing in the standard.

The machine is provided with the customary base 1 and its standard 2 rising therefrom, the rotary knife 3 being journaled at one side of the standard, and the electric motor 4 for driving the knife constituting the superstructure of the machine.

The vertical shaft 5 of the armature 6 of this motor drives the knife by means of a bevel pinion 7 at its lower end meshing with the large bevel knife gear 8 through an opening 9 in the standard. The motor has 35 a single horse-shoe field magnet 10, illustrated in detail in Fig. 4, whereof the pole pieces 11 are disposed toward the front and back of the machine and a connecting core 12 with a single exciting coil 13 thereon at 40 the side away from the knife. At this side of the machine, accordingly, the motor projects to a substantial distance, as seen in Fig. 3, but at the opposite side its external lines lie comparatively close to the plane of 45 the knife. The base 1, it will be understood, is of adequate width to prevent any over-balancing tendency, in addition to which the amount of overhang at the "off" side may be minimized by forming the coil 13 of 50 a flat oval form with its major axis vertical.

By virtue of the described construction the operator is afforded an advantageously clear view of the knife and of the progress of the cut, and, there being no coils at the 55 back of the machine, the handle 14, which is shown broken away in the views, may be shortened so that its grip is brought nearer to the machine, with the consequent advantage already noted. The field magnet as 60 preferably constructed has its pole pieces and core formed separately and united by bolting or screwing, and the pole pieces are comparatively narrow and are curved at the extremities, as shown in Fig. 4.

Means are provided for housing and ven-

tilating the upper portion of the motor, including the commutator 16 and brushes 17, in the following manner: 18 is an upper casting secured to the top of the field magnet and having uprights 19 carrying the 70 brushes (only one upright and brush being shown) and a head 20 connecting these uprights and containing the upper bearing 21 of the armature shaft. The said upper casing is also provided near its periphery 75 with an upstanding flange 22, which is encircled by the depending skirt of a cover 23, the latter having a central opening whereby it may be placed over the head 20 to rest upon a shoulder of the supporting structure, as seen in Fig. 1, and being held in place by a cap 24 screwed onto the head 20. The interior of the skirt 23, where it overlaps the upstanding flange 22, is fluted or provided with air channels, substantially as 80 shown in Fig. 2 for example, thereby permitting free access of air to the parts subject to heating without danger of injury to these parts by tampering or otherwise.

The grinder, which is located at the front 90 of the machine, comprises a vertical stem 25 slidable in a boxed guide 26 secured to the front of the field frame portion of the machine at the side remote from the field coil 13. The stem is preferably rectangular in 95 cross-section and the guide 26 formed in two halves united by screws 27, by which from time to time any lost motion due to wear may be taken up. At its lower end the stem carries or is united with a substantially U-shaped yoke 28, the latter being offset from the stem toward the plane of the knife and having its bracket arms 29 extending rearward beneath the overhang of the motor. In the preferred construction 100 of the grinder these arms are curved to form split eyes 30 for the clamping reception of individual bearings 31, these bearings or either of them being quickly adjustable in axial directions by loosening the 105 screws 32 of the eyes, slipping the bearings endwise, and again tightening the screws. The shaft 33 of each of the grinder disks 34 preferably consists of a screw stud having a plain portion revolvable in its bearing, its 110 head 35 at the outer end and its reduced threaded portion 36 at the inner end for engagement by a nut 37 which is received and held within a central recess 38 of the stone. As illustrated in Fig. 7, the said 115 recess is of two diameters and the nut 37 has a reduced portion 39 to fit the smaller portion of the recess and a relatively enlarged head 40 which overlies and bears against the shoulder in the recess. In assembling these 120 parts, the screw stud 33 is turned by means of a screw driver, the nut 37 being preferably fixed in the stone, until the outer side of the stone is brought to bear against a washer 41, and the latter in turn against 125

the shoulder of the stud formed at the junction of the plain and threaded portions 33 and 36. It will be understood that the portions are such that when the stud and stone 5 are thus united rigidly together, there is sufficient slight play between the head 35 and the washer 41 on the one hand and the ends of the bearing 31 on the other hand to permit of free turning of the shaft in its bearing. This mounting for the individual stones is simple and inexpensive, holds the stones with exceptional firmness, and permits quick and easy adjustment of the stones with reference to the plane of the knife edge. 10 The knife guard comprises a plate 42, which is hinged to the standard at its rear end, as shown at 43, the hinge being located above and at the rear of the knife and its axis being vertical. A curved adjustable 15 extension or guard proper 44 projects forward and downward from the hinged plate 42 and is adjustable in a curved path thereon, by virtue of a slot 45 which receives a pair of headed guiding studs 46 projecting 20 from the said plate. The adjustable piece is held frictionally and firmly at any degree of adjustment by means of a curved spring plate 47, shown in Figs. 1 and 5, through 25 which the studs 46 pass, its ends bearing against their heads and its central portion pressing against the side of the slidable 30 piece.

The guard and grinder are operated jointly by means of a slide 48 extending 35 fore and aft of the machine, and guided in bearings 49. The rear end of this slide carries a thumb piece or handle portion 50, located in convenient proximity to the main handle 14 of the machine, so that it may be 40 pressed forward by the thumb of the hand resting thereon. The forward portion of the slidable member is inclined, as shown at 51, and operated between a pair of roller bearing studs 52 on the stem 25 of the 45 grinder. The operating member 48 also has a downward extension 53 carrying a shoe 54 having an inclined or cam portion 55 (see Fig. 5) which acts upon a projection 56 on the hinged plate 42 of the guard. 50 When the operating member 48 is moved forward, the lower surface of its inclined portion 51 forces the grinder downward to bring the grinder disks into engagement with the knife. Simultaneously the shoe 54 forces the guard outward, as represented 55 by full lines in Fig. 3 and by dotted lines in Fig. 5. When the thumb pressure is removed, the operating member is moved rearward so as to restore it to normal position by means of a spring 57, and in this movement the upper face of the inclined portion 51 raises the grinder disks upward away from the knife. At the same time the cam portion 55 passes rearward from the 60 projection 56, so as to permit the guard 65

to be swung back to guarding position by its spring 58. In normal position the guard is locked against undesired outward movement by a hook 59 on the forward end of the shoe 54, this hook taking over the projection 56 as clearly shown in Fig. 5.

The cloth raiser 60 is located upon the forward portion of the base directly in front of and beneath the edge of the knife. The cloth raiser normally lies flat, as shown in 75 Figs. 1 and 9, and is provided with a knife slot 61, which permits it to be tilted about its forward portion, by suitable linkage, to the position of Fig. 8. In its operation the cloth raiser has a bodily rearward movement 80 as well as the tilting movement, whereby the plies of cloth are presented more effectively to the edge of the knife in cutting corners. In the particular construction shown, the cloth raiser has a pair of ears 62 projecting 85 downward from its forward portion through guide slots 63 in the base, and between these ears is loosely pivoted the forward end of a pull link 64, the rear end of which is pivotally connected to a crank arm 65 on the 90 lower end of a rock-shaft 66, which rock-shaft rises into proximity to the main handle of the machine and is there provided with a finger piece or handle portion 67. The pivoting of the link 64 at the points 95 68 and 69 is sufficiently loose to permit of the components of lateral and up and down swing of this link incident to its longitudinal movement. When rearward draft is exerted upon the link 64 the cloth raiser 100 60 is drawn rearward and tilted, the tilting being most pronounced when the rear edges of the ears 62 strike the rear ends of the slots 63, as shown in Fig. 8. For the purposes of the tilting movement the upper 105 surface of the base is preferably hollowed out beneath the forward part of the cloth raiser, as appears at 70 in Fig. 8. Restoration of the cloth raiser and its operating mechanism to normal position is effected by 110 a spring 71.

The mounting of the knife and knife gear are illustrated more particularly in Fig. 11. As there indicated, the standard is provided with a circular recess, which receives the 115 ball bearing 72. The outer race of this ball bearing is secured fixedly in this recess and its inner member 73 has the knife 3 and knife gear 8 detachably connected thereto. For this purpose a headed stud 74 is passed 120 through the inner member 73 of the ball bearing with its head in contact with the rear side thereof and its projecting end entered into a circular opening in the middle of the gear 8. A cap screw 75 has a large 125 head which overlies the outer faces of the gear and the knife, which latter is mounted on an annular shoulder 76 on the gear, and its threaded shank engages an internally threaded cavity in the stud 74. In this way 130

the knife is held upon the knife gear, and the latter is fixedly secured to the rotary member 73 of the ball bearing. By simply unscrewing the cap screw 75, the knife and 5 knife gear may be removed, leaving the ball bearing and stud 74 in place in the standard. In order to keep the stud 74 from turning when the cap screw 75 is applied or removed, an opening 77 may be formed 10 through the bossed portion 78 of the standard, in order to permit a pin to be inserted into a recess 79 which may be caused to register with this opening. The gear 8 is of dished formation, its teeth being formed 15 upon a flange which extends into an annular recess 80 in the standard concentric with the recess carrying the ball bearing. In this way any particles of dirt, in order to reach the bearing, would have to pass through a 20 narrow and circuitous path, with the result that the bearing is effectually protected and requires to be cleaned only at comparatively long intervals.

In conclusion I would state that while I 25 have illustrated the preferred embodiment of my invention and described the same in detail, it is to be understood that numerous changes may be made without departing from essentials and that I do not necessarily 30 limit myself to the precise details of construction shown.

What I claim as new is:

1. In a rotary knife cloth-cutting machine, 35 the combination with the rotary knife and framework, of a grinder having a mounting wherein it may slide vertically on the framework of the machine, a knife-guard mounted to swing about a vertical axis toward the rear of the framework, and a common operating member mounted for fore and aft movement on the framework and having means for operating both the guard and the 40 grinder.

2. In a rotary knife cloth-cutting machine, 45 the combination of a vertically slidable grinder, a knife guard hinged at its rear portion to swing about a vertical axis, and an operating member mounted for forward and backward movement and having inclines for operating said guard and grinder.

3. In a rotary knife cloth-cutting machine, 55 the combination of a vertically slidable grinder having a pair of abutments, a knife guard hinged to swing about a vertical axis, and an operating slide movable fore and aft on the machine and having an oblique forward portion operating between said abutments, the slide also having an incline in rear of said oblique portion to act upon the 60 guard.

4. In a rotary knife cloth-cutting machine, 125 the combination of a vertically slidable grinder, a knife guard hinged to swing about a vertical axis, and an operating slide having

movable fore and aft on the machine and 65 having an incline at its forward portion for effecting the vertical movement of the grinder, another incline for effecting the lateral swinging of the guard, and a hook which normally locks the guard against 70 movement.

5. In a rotary knife cloth-cutting machine, the combination of a grinder having a vertical stem, a guide slidably receiving said stem, a yoke carrying grinder disks on the 75 lower end of the stem, and a fore and aft movable operating slide having an incline for depressing the grinder.

6. In a rotary knife cloth-cutting machine, 80 the combination of a grinder having a mounting wherein it slides vertically, and a fore and aft movable operating member having an incline for effecting the vertical movement of the grinder.

7. In a rotary knife cloth-cutting machine, 85 the combination with the knife, of a vertically slidable grinder having a pair of abutments, a horizontally slidable operating member 90 extending fore and aft of the machine and having an oblique portion operating between said abutments, and a spring acting upon the said member to restore the same and the grinder to normal position.

8. In a rotary knife cloth-cutting machine, 95 the combination with the knife and standard, of a grinder having a slide portion guided for vertical movement above and toward the front of the knife and a yoke comprising rearward extending arms, and 100 grinder disks carried by said arms.

9. A rotary knife electric cloth-cutting machine, comprising a base, standard, knife and motor for driving the knife, and in combination therewith, a grinder having a slide 105 portion guided for vertical movement adjacent the front of the frame of the motor, and arms extending rearward from the lower part of said slide portion and carrying grinder disks beneath the overhang of the motor.

10. In a rotary knife electric cloth-cutting machine, the combination with the knife, of a knife guard hinged at its rear portion to swing about a vertical axis to clear the knife 115 edge.

11. In a rotary knife electric cloth-cutting machine, the combination with the knife, of a knife guard hinged at its rear portion to swing about a vertical axis to clear the knife edge, and a member guided for movement forward and rearward on the framework of the machine and having an incline for swinging the guard.

12. In a rotary knife electric cloth-cutting machine, the combination with the knife, of a knife guard hinged at its rear portion to swing about a vertical axis to clear the knife edge, and an operating slide having

- an incline for swinging the guard outward by a wedging action exerted adjacent its hinge.
13. In a rotary knife electric cloth-cutting machine, a knife guard having a vertical hinge mounting at its rear portion, and a reciprocatory operating member having an incline positioned to bear upon the guard adjacent the hinge to swing the same away from the knife.
14. In a rotary knife electric cloth-cutting machine, a knife guard having a vertical hinge mounting at its rear portion, and a reciprocatory operating member having an incline positioned to bear upon the guard adjacent the hinge to swing the same away from the knife, the said operating member also having a portion which normally locks the guard.
15. In a rotary knife electric cloth-cutting machine, the combination of a hinged knife guard, and an operating slide having an incline to swing the guard outward, and a hook on the slide normally detaining the guard.
16. In a rotary knife electric cloth-cutting machine, and in combination with the base, standard and rotary knife on the standard, a cloth raiser mounted to slide rearward and forward and to tilt upon the base beneath the forward portion of the knife.
17. In a rotary knife electric cloth-cutting machine, a cloth raiser having a slidable and tilting mounting and linkage for operating the same.
18. In a rotary knife electric cloth-cutting machine, and in combination with the base, standard and rotary knife on the standard, a cloth raiser tiltable about its forward portion on the base and also slidable thereon, a downward projection on the forward part of the cloth raiser, and means for exerting rearward draft upon said projection.
19. In a rotary knife electric cloth-cutting machine, the combination of the base having a longitudinal slot, a cloth raiser having a downward projecting lug on its forward portion guided in said slot, and means con-
- nected with said lug for drawing the same rearward to fulcrum against the rear end of 50 the slot.
20. In a rotary knife electric cloth-cutting machine, the combination of the base having a longitudinal slot, a cloth raiser having a portion operating in said slot and adapted 55 to fulcrum against the rear end thereof, whereby the raiser has sliding and tilting movement, and suitable operating connections for effecting such movement.
21. In a rotary knife electric cloth-cutting machine, the combination of the standard having a recess, a ball bearing comprising outer and inner members with balls between, the outer member being fixed in said recess, a headed stud passed through the inner 65 member of the ball bearing and rotatable therewith, a knife gear, and a screw engaging said stud and having a head overlying the outer face of the knife gear.
22. In a rotary knife electric cloth-cutting machine, the combination of the standard having a recess, a ball bearing comprising outer and inner members with balls between, the outer member being fixed in said recess, a knife gear, a knife centered on the knife 75 gear, and a cap screw securing the knife to the knife gear and both to the inner member of the ball bearing.
23. In a rotary knife electric cloth-cutting machine, the combination of a knife gear, 80 a knife against the knife gear, a rotary support, and a single central screw for holding the knife to the knife gear and both to said rotary support.
24. In a rotary knife electric cloth-cutting 85 machine, the combination of a standard having a recess, a ball bearing seated in said recess, a knife and knife gear at the side of the standard, and a detachable connection between the knife gear and the ball bearing, 90 the knife gear being dished with its tooth flange projecting into an annular recess in the standard, whereby the bearing is further protected.

ALBERT P. KOMOW.
